His Attorney.

UNITED STATES PATENT OFFICE.

ERNST F. W. ALEXANDERSON, OF SCHENECTADY, NEW YORK, ASSIGNOR TO GENERAL ELECTRIC COMPANY, A CORPORATION OF NEW YORK.

WIRELESS SIGNALING SYSTEM.

1,313,042.

Specification of Letters Patent. Patented Aug. 12, 1919.

Application filed November 26, 1917. Serial No. 203,915.

To all whom it may concern:

Be it known that I, ERNST F. W. ALEXANDERSON, a citizen of the United States, residing at Schenectady, in the county of 5 Schenectady, State of New York, have invented certain new and useful Improvements in Wireless Signaling Systems, of which the following is a specification.

My present invention relates to wireless 10 signaling systems, and more particularly to a so-called "duplex system" in which means is provided for simultaneously sending and receiving messages at a single station.

The object of my invention is to provide 15 means for neutralizing in the receiving circuit or apparatus the effect of waves which are being transmitted from the same station. My present application is a continuation in part of my prior application, Serial No. 20 143,491, filed January 20, 1917.

In carrying my invention into effect I employ separate antennae for transmitting and receiving purposes. Both of these antennae may be suspended from the same towers in 25 whole or in part, or may be located in fairly close proximity to each other upon separate towers. In order to overcome the effect in the receiving apparatus of the waves impressed upon the receiving antenna from the transmitting antenna, I derive from the 30 transmitting antenna, an electromotive force equal in value and opposite in direction to the potential induced upon the receiving antenna from the transmitting antenna and impress this electromotive force upon the receiving circuit in such a manner as to neutralize in the receiving apparatus the effect of the induced potential.

The novel features which I believe to be 40 characteristic of my invention are set forth with particularity in the appended claims. The invention itself, however, both as to particular embodiments thereof and its mode of operation, will be best understood 45 by reference to the following description taken in connection with the accompanying drawing in which Figures 1 and 2 show two modifications of my invention, and Fig. 3 is a diagram explanatory of the form shown 50 in Fig. 2.

In Fig. 1, I have indicated a transmitting antenna 1 supported upon towers 2 and 3. A receiving antenna 4 which is insulated from the transmitting antenna is supported 55 upon towers 3 and 5. The receiving antenna

may be supported upon the towers 2 and 3 or may be supported independently of either of these towers but in close enough proximity to the transmitting antenna so that both antennae may be readily connected to 60 the operating station. The transmitting antenna may be supplied with signaling current from a high frequency alternator 6 coupled thereto by means of the coils 7 and 8. The tuning of this antenna may be accomplished by means of the usual variable inductance 9. The receiving antenna 4 is connected to earth at 10 through the coil 11 which is coupled to the coil 12 in the receiving circuit of the electron discharge device 70 13 which may serve as an amplifier and detector for the signals which it is desired to receive. The receiving circuit comprises the cathode 14 of the device, the grid 15 and a variable condenser 16 for tuning the circuit 75 to the frequency of the waves to be received. The detector circuit of the device comprises the cathode 14, anode 17, a battery 18 for supplying the operating current, and the usual telephone receivers 19, these receivers 80 being shunted by the condenser 20 which serves to by-pass the high frequency component of the current flowing in the circuit. While the arrangement shown is a preferred 85 form of receiving device other forms may be employed if desired.

With the system thus far described, when signals are being transmitted potentials of such magnitude will be induced in the receiving antenna that the received signals will 90 be unintelligible even though the two sets of signals may differ considerably in frequency. To overcome this difficulty I provide a shunt connection to the transmitting antenna from the point 21 to earth at 22 95 through the inductance 23. The inductance 24 is coupled to inductance 23 in such a way that the potential induced therein is equal and opposite to that induced from transmitting antenna 1 upon receiving antenna 4. 100 The potential thus obtained is impressed upon the receiving antenna by means of the connecting wire 25, a variable condenser 26 being included in the circuit for tuning it to the frequency of the transmitting current. 105 The two opposing potentials thus neutralize each other and as a result the receiving apparatus will not be affected by the waves transmitted from antenna 1. If any difficulty is experienced in adjusting the neu- 110

tralizing circuit in such a way as to entirely overcome the effect of the transmitted waves a frequency trap consisting of a condenser 27 and inductance 28 may be inserted in the 5 receiving circuit. If this frequency trap is tuned to the frequency of the waves transmitted it will offer a high impedance to waves of that frequency and a much lower impedance to received waves which differ 10 somewhat in frequency from the waves transmitted. I have indicated as a means for controlling the current in the antenna a switch 29. It will, of course, be understood, however, the antenna current may be 15 controlled in any desired way for transmitting either telegraphic or telephonic signals.

In the form of my invention shown in Fig. 2 the main neutralization of the induced potentials in the receiving antenna is accomplished by an arrangement of electrostatic condensers with an additional electromagnetic coupling for obtaining a final adjustment of the system. The neutralization effect 20 in this case is to the highest possible degree independent of the frequency and, therefore, a higher degree of neutralization is possible. The neutralization is also substantially independent of fluctuations in the 25 operation of the transmitting apparatus and the regulation of the system is simple. The operation of this system is based upon the Wheatstone bridge principle and will be best understood by reference to the diagram 30 of Fig. 3. In this diagram the condenser 30 represents the capacity between the receiving aerial 4 and ground. The corresponding capacity on the other side is the condenser 31 which I term the "counterpoise" condenser. This is inserted in the 35 ground connection of the receiving antenna as indicated in Fig. 2. The capacity of the receiving aerial is fixed by the antenna structure and the counterpoise condenser has a 40 fixed capacity which is not changed during the operation of the system. The third arm of the bridge which I term the "exposure capacity of the receiving aerial" comprises the natural capacity between the transmitting and receiving antennae and is represented by the condenser 32. This capacity 45 also is determined by the antenna structure and is substantially constant. To balance this exposure capacity I employ a condenser 50 33 which I term the "exposure capacity of the counterpoise." The condenser 33 may be of such a value as to balance the system so that the points 34 and 35 at the ends of the receiving coil 11 are at substantially 55 equal potentials in so far as the transmitted waves are concerned. In this arrangement the potential across the capacity 32 represents the induced potential on the receiving antenna and the potential across condenser 60 65 33 is a potential derived directly from the

transmitting antenna which is connected to the receiving coil 11 in such a way as to neutralize therein the effect of the potential across capacity 32.

When the electrostatic balance which I 70 have described is employed, I have found that it is desirable that the receiving set should be screened from the effect of any electrostatic field which may be produced in the receiving coil 11. In order to accomplish this purpose I have indicated in Fig. 2 a metallic shield 36 surrounding the coil 11, this shield being grounded and split vertically in such a way as to prevent the short circuiting of the magnetic lines of force. 80 The switch 37 for adjusting the inductance of coil 11 is also inclosed within this shielding member 36. In this case instead of coupling the coil 11 directly to the coil 12 I may employ an intermediate coupling circuit comprising a coil 38, of a few turns wound around the shield 36 and a second coil 39 in circuit with coil 38 and which is coupled to the coil 12.

In actual practice it may be found desirable to proportion the condensers 31 and 33 so as to bring the system to an approximate balance. The final balancing adjustment may then be very conveniently made by the use of an additional electromagnetic coupling between the transmitting and receiving systems. I have indicated in Fig. 2 the manner in which this may be brought about. As here shown a potential is derived from the transmitting system by the coil 40 which 90 is coupled to coil 8. The potential obtained by means of this coil is applied to the grid circuit of detector 13 by means of coil 41 which is coupled to the coil 12, the coupling between these two coils being adjustable so 100 that by varying this coupling the desired balance between the systems may be effected.

It will be noted that in the arrangement shown in Fig. 1 the electromagnetic coupling is made to the primary of the receiving set. It may be found in practice that the receiving apparatus will be influenced by strays other than those received directly on the antenna. If this is the case, these strays will not vary in intensity in the same 115 manner as the transmitted signals and in order to maintain a balance in the system frequent adjustment may be necessary. It will be found that less adjustment will be required and that the adjustment may be 120 made more easily and conveniently if the electromagnetic coupling is applied to the secondary of the receiving set as indicated in Fig. 2, as in this arrangement the compensating electromotive forces do not have 125 to pass through the transformation between primary and secondary of the receiving system but are applied directly to the part of the circuit where their effect is desired. For this reason, in case the electromagnetic cou- 130

pling alone is used for compensation it may be desirable to arrange it in the manner indicated in Fig. 2.

While I have shown and described only two modifications of my invention, it will be apparent that many variations in the circuit arrangements used and the form of apparatus employed may be made without departing from the scope of my invention as set forth in the appended claims.

What I claim as new and desire to secure by Letters Patent of the United States, is:

1. The combination in a wireless signaling system of a receiving antenna, a separate transmitting antenna in proximity thereto, and a receiving system comprising a receiving coil having one end connected to said receiving antenna and its opposite end connected to a point between two capacities, one of which is connected to earth and the other of which is connected to the transmitting antenna, and an electromagnetic coupling between the transmitting antenna system and the receiving system.

2. The combination in a wireless signaling system of a receiving antenna, a separate transmitting antenna in proximity thereto, a receiving system comprising a receiving coil having one end connected to said receiving antenna and its opposite end connected to a point between two capacities, one of which is connected to earth and the other of which is connected to the transmitting antenna, the two capacities being so proportioned with respect to the capacity of the receiving antenna and the mutual capacity between the antennæ, that the two ends of the coil are at substantially equal potentials with respect to the transmitted waves, and an electromagnetic coupling between the transmitting antenna system and the receiving system.

3. The combination in a wireless signaling system of a receiving antenna, a separate transmitting antenna in proximity thereto, a receiving system comprising a receiving coil having one end connected to the receiving antenna and its other end connected to a point which is of substantially equal potential, with respect to the transmitted waves, and an electromagnetic coupling between the transmitting antenna system and the receiving system.

4. The combination in a wireless signaling system of a receiving antenna system comprising primary and secondary circuits, a separate transmitting antenna in proximity thereto, the primary circuit of said receiving system comprising a receiving coil having one end connected to the receiving antenna and its opposite end connected to a point be-

tween two capacities, one of which is connected to earth and the other of which is connected to the transmitting antenna, and an electromagnetic coupling between the transmitting antenna system and the secondary circuit of the receiving system.

5. The combination in a wireless signaling system of a receiving antenna system comprising primary and secondary circuits, a separate transmitting antenna in proximity thereto, the primary circuit of said receiving system comprising a receiving coil having one end connected to the receiving antenna and its opposite end connected to a point between two capacities one of which is connected to earth and the other of which is connected to the transmitting antenna, the two capacities being so proportioned with respect to the capacity of the receiving antenna and the mutual capacity between the antennæ that the two ends of the coil are at substantially equal potentials with respect to the transmitted waves, and an electromagnetic coupling between the transmitting antenna system and the secondary circuit of the receiving system.

6. The combination in a wireless signaling system of a receiving antenna system comprising primary and secondary circuits, a separate transmitting antenna in proximity thereto, the primary circuit of said receiving system comprising a receiving coil having one end connected to the receiving antenna and its other end connected to a point which is of substantially equal potential with respect to the transmitted waves and an electromagnetic coupling between the transmitting antenna system and the secondary circuit of the receiving system.

7. The combination in a wireless signaling system of a receiving antenna system comprising primary and secondary circuits, a separate transmitting antenna system in proximity thereto, the primary circuit of said receiving system comprising a receiving coil having one end connected to the receiving antenna and its other end connected to a point which is at substantially equal potential with respect to the transmitted waves and an electromagnetic coupling between a source of radiations and the secondary circuit of said receiving system whereby electromotive forces may be impressed upon the receiving system which are opposite in directions to the electromotive forces produced therein by radiation from the transmitting antenna system.

In witness whereof I have hereunto set my hand this 23rd day of November, 1917.

ERNST F. W. ALEXANDERSON.
